FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

METHOD AND APPARATUS FOR CONDITIONING PREPARED FABRIC.

1,350,366.

Specification of Letters Patent. Patented Aug. 24, 1920.

Application filed November 1, 1918. Serial No. 260,637.

To all whom it may concern:

Be it known that I, FREDERICK M. FURBER, a citizen of the United States, residing at Revere, in the county of Suffolk and 5 State of Massachusetts, have invented certain new and useful Improvements in Methods and Apparatus for Conditioning Prepared Fabric; and I do hereby declare the following to be a full, clear, and exact 10 description of the invention, such as will enable others skilled in the art to which it appertains to make and use the same.

This invention relates to a method of conditioning material and more particularly coated canvas or similar reinforcing fabric employed in the manufacture of reinforced insoles, and to an apparatus for carrying out the method.

The fabric employed in the manufacture 20 of Gem and like insoles is usually coated upon one side with a composition which at ordinary temperatures is non-adhesive, but which is made adhesive upon the application of a certain degree of heat to the fabric. Fabric thus coated is known in the art as "prepared fabric" and, for convenience, this term will hereinafter be employed in referring to such fabric. Considerable difficulty has been experienced in 25 heating prepared fabric in such manner as to cause its coating to be uniformly adhesive and free from blisters, and the fabric maintained substantially dry and yet sufficiently pliable to be molded properly about 30 the lip of the insole blank.

Accordingly, the primary object of the present invention is to devise an improved mode of heating prepared fabric for application to insole blanks.

40 To the accomplishment of this object and such others as may hereinafter appear, as will be readily understood by those skilled in the art, the invention comprises the features and combinations of parts hereinafter 45 described and particularly pointed out in the appended claims.

The preferred form of the invention is shown in the accompanying drawings, in which:—

50 Figure 1 is a view in perspective of the apparatus from its rear;

Fig. 2 is a plan view of the apparatus partly broken away;

Fig. 3 is a longitudinal sectional view taken on the line 3—3 of Fig. 2; and 55

Fig. 4 is a transverse sectional view taken on the line 4—4 of Fig. 2.

The apparatus illustrated in the drawings is provided with a horizontal elongated closed casing 6, which is supported at 60 its ends by standards 8—8. It is not essential that the casing have a cover. When a cover is employed it comprises preferably a plate 10 of cement or other porous material. Confined within the casing is a heating device 12 and a water container 14. The heating device consists of a pipe coiled in a horizontal plane, located between the top side of the casing and the water container, having inlet and outlet ends located 70 at the rear of the casing at opposite ends thereof. Steam is admitted to the heating device through a pipe 16 and a valve 18, and after passage through the coils of the heating device, a part of the steam is conducted from the apparatus by means of a pipe 20 connected to the outlet end of the heating device, and the remaining portion of the steam enters a condenser 22 through a pipe 24. The condenser 22 consists of a 75 coiled pipe depending at the rear of the apparatus, and the steam during its passage therethrough is condensed by the cool air. The water of condensation is conducted through a pipe 26 and a stop-cock 28 to a 80 funnel 30 located at a higher level than the top of the water container. The funnel 30 forms a water reservoir which is connected through a pipe 32 with an inlet opening 34 in the bottom of the water container. The 85 water container, which is centrally positioned on the bottom of the casing, is of a height and width less than that of the inside of the casing. Its walls are thus spaced from the sides and ends of the casing. The 90 space in the casing surrounding the heating device 12 and the top, side and end walls of the water container, is filled with sand or other granular or porous material 95 36 which will diffuse heat and moisture uniformly.

The side and end walls of the water container are perforated, as best shown in Fig. 4, forming outlets to permit water from the container to diffuse into the sand in the 105 lower portion of the casing. The water is

prevented from rising above a certain level in the casing by an overflow pipe 38. The heat supplied by the heating device raises the temperature of the water sufficiently to cause vapor to rise therefrom and uniformly diffuse through the intervening portion of the sand and through the porous plate 10, if a cover is employed. This vapor serves as a conductor of the heat supplied by the heating device such that the sand 36, and, by conduction, the plate 10 is uniformly heated thereby. The amount of vapor absorbed by the porous plate 10 and which finally reaches its top surface is only sufficient to slightly, but uniformly, moisten the uncoated surface of a strip of prepared fabric placed upon the plate 10, without appreciably penetrating the fabric. The degree of moisture is sufficient to cause the fabric to be in a pliable condition when applied to the insole blank such that it may be molded properly about the lip of the insole, and the heat supplied by the heating device is of sufficient intensity to cause the fabric to be thoroughly dry immediately after being applied to the blank. The moistened granular material and porous plate evenly transmit the heat supplied by the heating device to the fabric, so that when the fabric is drawn from the apparatus, its coating is in a uniformly adhesive state.

The relative amounts of heat and vapor supplied to the plate 10 may be varied for different work by means of the stop-cock 28 which controls the supply of water to the water container and hence controls the amount of vapor which is diffused through the sand. By closing the stop-cock 28 the moistening means may be disconnected and the apparatus employed simply as a heater.

The strips of coated fabric are usually furnished to the manufacturer of reinforced insoles in rolls 39 and, accordingly, a spindle 40 is removably secured to the rear standard 45 for supporting a roll of fabric to be treated by the apparatus. In order to assist the operator in guiding the fabric from the roll and over the plate 10, a guide roll 42 for the fabric is mounted in brackets at one end of the casing 6.

A cutting table 44 is secured to the forward end of the casing 6 upon which the heated fabric may be laid to be severed and then applied to the insole blanks in the usual manner.

When the apparatus is not in use the end of the fabric strip is held out of contact with the apparatus by a bracket 46. The bracket 46 consists of a vertical rod having its lower end threaded into a wall of the casing and its upper end bent at right angles over the casing to form a horizontal support, over which the operator may suspend the end of the fabric at the completion of his stint of work.

It is to be understood that while the apparatus is particularly adapted for heating coated fabrics, the invention is not limited to such use except as defined in the claims, and moreover the invention is not limited to any particular apparatus or type of apparatus, or to any particular construction and arrangement of parts of the illustrated embodiment, but may be embodied in any form within the scope of the following claims.

What is claimed as new is:—

1. Apparatus of the class described having, in combination, porous material, means for saturating said material with moisture, and means for supplying heat through said material to heat an article positioned thereon.

2. Apparatus of the class described having, in combination, a casing, a water container having openings for discharging water into the casing, a heating device with in the casing adjacent said discharge openings in the water container, and granular material surrounding said openings and heating device.

3. Apparatus for conditioning prepared fabric having, in combination, a porous material against which the uncoated side of the fabric is positioned, means for supplying heat and moisture to said material, and means for relatively varying the amount of heat and moisture supplied to said material.

4. Apparatus of the class described having, in combination, a closed casing having one side composed of porous material, a water container having outlets opening into the casing, and a heating device between the water container and said side of the casing.

5. Apparatus of the class described having, in combination, a closed casing having one side made of porous material, a water container opening into the casing, a heating device between the water container and said side, and granular material surrounding the heating device.

6. Apparatus of the class described having, in combination, a casing having one side made of porous material, a water container opening into and within the casing, a heating device between and spaced from the water container and said side, and granular material filling the casing.

7. Apparatus of the class described having, in combination, a casing, a water container opening into and within the casing, a steam heating device between the water container and the top of the casing, and means for condensing the steam after it leaves the heating device and for conducting the water of condensation into the water container.

8. Apparatus of the class described having, in combination, a casing, a water container opening into and within the casing, a steam heating device between the water container and said side, means for condensing a portion of the steam after it leaves the

- heating device and for conducting the water of condensation into the water container, and means for regulating the supply of water to the container.
5. Apparatus of the class described having, in combination, an elongated casing having its cover made of porous material, a water container within and adjacent the bottom of the casing, said water container having its walls provided with perforations, a steam heating device between and spaced from said cover and the water container, means for condensing steam after it has passed through the heating device and conducting it to the water container, and granular material filling the casing.
10. Apparatus of the class described having, in combination, a casing, a water container within the casing having openings 20 for the passage of moisture into the casing, and a heating device between the water container and the top of the casing for heating the moisture passing into the casing.
15. Apparatus for conditioning prepared fabric having, in combination, a casing, a water container within the casing having water outlets, a heating device within the casing located above the water container, and granular material packed about said water container and heating device.
20. Apparatus for conditioning prepared fabric having, in combination, a casing having one side made of porous material, granular material within the casing, means for diffusing water through a portion of the granular material, and means for heating the water to cause vapor to diffuse through said side of the casing.
25. The method of conditioning prepared fabric which comprises applying the fabric with its uncoated side against porous material, diffusing moisture through the porous material, and applying heat to the porous material.
30. The method of conditioning prepared fabric which comprises simultaneously applying heat and a relatively slight degree of moisture to the uncoated side of the fabric.
35. The method of conditioning prepared fabric which comprises applying to the uncoated side of the fabric heat and a relatively slight degree of moisture diffused through a porous material.
40. The method of conditioning a prepared fabric which comprises applying heat and moisture to the uncoated side of the fabric through the medium of a porous material.
45. An apparatus of the class described having, in combination, a casing embodying a support for the article to be treated and a receptacle for water located beneath the support, a steam heating device for heating the casing and for supplying water to the receptacle by condensation of the steam, and means for conducting moisture from the water in the receptacle to said support.
50. An apparatus of the class described having, in combination, a casing providing a support for the article to be treated, means for heating the interior of said casing with steam, means for collecting the water of condensation from said steam, and provision for vaporizing said water of condensation to provide moisture in the heat transmitted to said article.
55. An apparatus of the class described having, in combination, a casing providing a support for the article to be treated, means for heating the interior of said casing with steam, means for collecting the water of condensation from said steam, and means for utilizing said water of condensation in treating the article on the support.
60. An apparatus of the class described having, in combination, a casing providing a support for the article to be treated, means for heating the interior of said casing with steam, means for collecting the water of condensation from said steam, a conduit for delivering said water to a point where it may be vaporized by said steam heat, and means for controlling the flow of water through said conduit.

FREDERICK M. FURBER.
